Primary Examiner — Kathleen L Jones(74) *Attorney, Agent, or Firm* — FisherBroyles, LLP(57) **CLAIM**

The ornamental design for a display screen with an animated graphical user interface, as shown and described.

DESCRIPTION

FIG. 1 is a front view of a first image in a sequence for a display screen with an animated graphical user interface showing the claimed design; and,

FIG. 2 is a front view of a second image thereof.

The broken lines shown in these figures showing a display screen, electronic device, and portions of a graphical user interface are for illustrative purposes only and form no part of the claimed design. The appearance of the transitional image sequentially transitions between the images shown in FIGS. 1-2. The process of period in which one image transitions to another image forms no part of the claimed design.
